US0D1091105S

(12) **United States Design Patent** (10) **Patent No.:** **US D1,091,105 S**
Chen (45) **Date of Patent:** **** Sep. 2, 2025**

(54) **BACKPACK**

(71) Applicant: **Guanxin Chen**, Guangzhou (CN)

(72) Inventor: **Guanxin Chen**, Guangzhou (CN)

(**) Term: **15 Years**

(21) Appl. No.: **29/957,229**

(22) Filed: **Aug. 13, 2024**

(30) **Foreign Application Priority Data**

Jun. 11, 2024 (CN) 202430353731.9

(51) **LOC (15) Cl.** **03-01**

(52) **U.S. Cl.**

USPC **D3/217**
